UNITED STATES PATENT OFFICE.

LOUIS H. WALES, OF NEW BRITAIN, CONNECTICUT, ASSIGNOR TO THE RUSSELL & ERWIN MANUFACTURING COMPANY, OF SAME PLACE.

DESIGN FOR A KNOB FACE OR CAP.

SPECIFICATION forming part of Design No. 32,316, dated March 6, 1900.

Application filed February 7, 1900. Serial No. 4,403. Term of patent 7 years.

To all whom it may concern:

Be it known that I, LOUIS H. WALES, a citizen of the United States, residing at New Britain, in the county of Hartford and State of Connecticut, have invented and produced a new and original Design for Knob Faces or Caps, of which the following is a specification, reference being had to the accompanying drawings, forming part thereof.

Figure 1 is a front elevation of a knob face or cap, showing my design. Fig. 2 is a side elevation of the same.

As shown in the drawings, the central figure consists of five conventional tulips 3, the stems 4 of which radiate from a common center. Surrounding the tulips is a series of crosslets 5, the series being in the form of a

ring. Surrounding these is a border-bead with a series of inwardly-pointed V-shaped offsets 6, all being on the slightly-convex central portion of the knob-face. Outside of this face there is a plane ovalo or quartic 7, then three narrower beads or rolls 8, and then a second ovalo or quartic 9.

Having described my invention, what I claim as new, and desire to secure by Letters Patent, is—

The design for a knob face or cap, as herein shown and described.

LOUIS H. WALES.
